UNITED STATES PATENT OFFICE.

ROBERT E. OSBORNE, OF HAMBURG, NEW YORK.

RAILROAD SPIKE.

1,416,971.

Specification of Letters Patent. Patented May 23, 1922.

Application filed October 6, 1921. Serial No. 505,816.

To all whom it may concern:

Be it known that I, ROBERT E. OSBORNE, a citizen of the United States, residing at Hamburg, in the county of Erie, State of New York, have invented a new and useful Railroad Spike; and I do hereby declare the following to be a full, clear, and exact description of the invention, such as will enable others skilled in the art to which it applies to make and use the same.

The invention relates to railroad and railway spikes and has for its object to economically incorporate a greater and more efficient holding principle for securely fastening the rails to the ties for preventing movement in a vertical direction. Also to provide spikes for preventing longitudinal creeping of the rails along the ties or sleepers, and for preventing upward displacement of the rails.

A further object is to provide a railroad spike comprising a shank, vertically disposed, elongated teeth on the inner face of said spike adjacent the head of the spike and adapted to bite into a rail flange for holding the rail against longitudinal movement. Also to provide the rear side of the spike with a plurality of spike holding teeth, said teeth being provided with horizontally disposed surfaces for biting into the tie and holding at a right angle to the line of strain on the spike, said teeth being provided with downwardly and inwardly inclined outer surfaces which allow the spike to be easily driven into a tie.

With the above and other objects in view the invention resides in the combination and arrangement of parts as hereinafter set forth, shown in the drawings, described and claimed, it being understood that changes in the precise embodiment of the invention may be made within the scope of what is claimed without departing from the spirit of the invention.

45 In the drawings:—

Figure 1 is a front elevation of the spike showing the rail flange engaging teeth.

Figure 2 is a side elevation of the spike.

Figure 3 is a rear elevation of the spike.

50 Figure 4 is a top plan view of the spike and a portion of a rail flange showing the vertically disposed teeth imbedded in the flange for preventing longitudinal movement of the rail.

55 Referring to the drawings, the numeral 1 designates the shank of the spike and 2 the

head thereof. Disposed on the inner face 3 of the spike beneath the head 2 and vertically disposed are elongated teeth 4, which teeth, when a spike is driven into cross-tie, 60 cut their way into or engage notches in the flange 5 of a rail as clearly shown in Figure 4 in such a manner as to hold the rail against longitudinal displacement or creeping. Upon the side 6 of the spike is a plurality of bevelled surfaces 7, which surfaces extend downwardly and inwardly and have their adjacent ends connected together by horizontally disposed surfaces 8 which form shoulders for engaging in a cross tie and 70 holding the spike against upward movement, the horizontally disposed surfaces increasing the bearing friction to create a more efficient bondage to the railroad tie. The upper inclined surface 7 has its upper end 9 extending outwardly beyond a vertical line between the upper ends of the other bevelled surfaces 7, thereby forming means whereby as the spike is forced into a railroad tie the teeth 4 will be forced inwardly in the direction 80 of the flange 5 of the railroad tie, thereby insuring a biting into the railroad rail flange by the vertically disposed bevelled teeth 4. When necessary the rail flange may be softened, for instance by annealing. The 85 lower end of the inner face 3 of the shank terminates in a downwardly and outwardly extending curved surface 10, which when the spike is driven into the tie forces the spike in the direction of the arrow 7, and 90 thus promotes the efficiency of the sloping surfaces 7 and the horizontally disposed surfaces 8 which are thrust against the fibres of the wooden tie.

In practice, when using the spike, it is to 95 be started into the wooden tie at a slight inclination, with the top or head 2 inclined inwardly in the direction of the rail, and with the point 11 tight against the flange 5. In the process of driving, as will be seen, the 100 point 11 will be forced outwardly in the direction indicated by the arrow 7 by the curved surface 10 at the point of the spike. When the spike has reached its maximum downward position, the head 2 resting on top 105 of the flange of the rail, the bevel formed by the inclined teeth 4 together with curved surface 10, will force the entire spike outwardly in the direction of the arrow 7 and thus the fibres of the wooden ties will be 110 forced over and around the horizontally disposed surfaces 8 on the outer side of the shank

of the spike. By reason of this wedging construction in the spike, it will require a greater force to withdraw it, the rail acting as the drawing medium. The forcing of the spike against the fibres of the wooden tie also produces an equal force of the teeth against the rail flange and thus produces the desired feature which eliminates the creeping of the rail in a horizontal direction along ties.

10 The invention having been set forth what is claimed as new and useful is:—

15 1. A railroad spike comprising a shank and a head carried by said shank, vertically disposed elongated teeth on the inner face of said shank and disposed adjacent the head thereof, the outer face of said shank being provided with downwardly and inwardly extending bevelled surfaces, thereby forming 20 horizontally disposed shoulders, the upper inclined surface having its upper end extending outwardly beyond vertical alignment with the upper ends of the inclined surfaces, the vertically disposed teeth inclined downwardly and inwardly, the lower end of said spike being provided with a curved surface which curves downwardly and outwardly from the inner face of the spike and forms 25

means for tilting the spike during its downward movement into a tie.

2. The combination with a railroad spike comprising a shank having a head thereon, of a sloping inner surface adjacent the head which head extends over and beyond said sloping surface, of teeth carried by the outer 35 face of said shank, said teeth being formed by downwardly and inwardly inclined surfaces having their adjacent ends connected together by horizontally disposed surfaces, the lower end of said spike being provided 40 with a curved or sloping surface which extends downwardly and outwardly from the inner face of the spike terminating in a chisel shaped point and acting in conjunction with the upper inner inclined surface for 45 the purpose of forcing the shoulders formed by the outer inclined surfaces against fibres of a wooden tie to increase the drawing resistance of the spike.

In testimony whereof I have signed my name to this specification in the presence of two subscribing witnesses.

ROBERT E. OSBORNE.
